UNITED STATES PATENT OFFICE.

THOMAS A. MACDONALD, OF PATERSON, NEW JERSEY.

TRUSS.

1,140,754.

Specification of Letters Patent.

Patented May 25, 1915.

Application filed September 3, 1914. Serial No. 859,991.

To all whom it may concern:

Be it known that I, THOMAS A. MACDONALD, a subject of the King of Great Britain, and a resident of Paterson, in the county of Passaic and State of New Jersey, have made certain new and useful Improvements in Trusses, of which the following is a specification.

My invention relates to surgical appliances, more particularly to trusses, and it consists in the combinations, constructions and arrangements herein described and claimed.

An object of my invention is to provide a device by means of which a rupture may be permanently healed in a comparatively short time.

A further object of my invention is to provide a device of the type described in which there is an adjustable pad that may be moved to withdraw pressure as the wound heals.

A further object of my invention is to provide a device of the type described which is particularly effective in preventing the protrusion of the viscera.

Other objects and advantages will appear in the following specification and the novel features of the device will be particularly pointed out in the appended claim.

My invention is illustrated in the accompanying drawings forming part of this application in which—

Figure 1 is a perspective view of the truss, Fig. 2 is a plan view of the pad, Fig. 3 is a section along the line 3—3 of Fig. 2, and Fig. 4 is a modified form of the device.

In carrying out my invention I provide a base or backing 1 which may be made of metal or other suitable material and which is provided with peripheral flanges 2. Disposed within the peripheral flanges and retained by them is an outer wall 3, which is preferably circular in cross section, as shown in Fig. 3, and which may be made of any suitable material such as leather stuffed with resilient packing, rubber, celluloid, etc.

Disposed on one side of the plate 1 is an inner plate 4 upon which the wall 3 bears. This inner plate forms a reinforcement for the plate 1. Straps 5 may be secured to the plates 1 and 4 by means of rivets 6 or in any other suitable manner, these straps being intended to fasten around the body and be-

ing provided with the usual buckle or clasp 55.

7. A cross strap 8 may be used if desired.

On the opposite side of the plate 1 from the wall 3 is a bowed member 9, which is provided with a lug or pin 10 at its center. The plate 4 is provided with a bracket 11 60 which is threaded to receive a screw bolt 12, an opening being provided in the plates 1 and 4 to permit the free passage of the screw. A milled nut 13 is disposed on the screw 12, while a spring 14 bears at one end 65 on the bowed member 9 and at the other end on the nut. The spring 14, as will be seen, surrounds the pin or lug 10 at one end and the end of the screw bolt at the other.

A central pad 15 is provided having a 70 plate 16 on its flat side which holds the head of the screw bolt 12 in place. This pad 15 may be made of any suitable material. It will be seen that the pad is spaced apart 75 from the wall 3.

From the foregoing description of the various parts of the device the operation thereof may be readily understood.

The straps 5 and 8 are secured to the body of the patient in the usual manner and the 80 central pad 15 is placed in the opening in the body of the patient. In Fig. 3 I have indicated diagrammatically the edges of the opening at α . It will be seen that the pad does not touch these edges and also that the 85 outer walls 3 of the body press against the body of the patient at some distance beyond the edges of the opening. In many devices of this type the pads are designed to completely cover the opening and where they 90 come in contact with the edges of the opening the patient suffers severe pain. Furthermore such a device prevents the union of the parts which are ruptured. In the present instance the central pad is designed 95 to hold back the viscera, but in the event that any portion of the viscera should protrude past the central pad, it will be held and retained in the cup formed by the walls 3 and the plate 4. Moreover since the walls 100 3 are in direct contact with the body of the patient the pad is not apt to slip since the walls 3 have sufficient friction to prevent such slipping. Therefore the central pad is held within the opening and does not come 105 in contact with the walls thereof. Now as the wound begins to heal, due to the fact that the viscera is held in its proper place,

the milled nut 13 is gradually turned so as to cause the retraction of the pad 15. This allows the wound to heal gradually and the nut may be moved by the patient himself as the wound heals.

It will be observed that the tension of the pad is not secured by tightening the belt, but rather by the spring 14 so that the belt need only be tightened sufficiently to keep the pad in place.

I am aware that devices have been made in which exterior walls have been used to prevent the protrusion of the viscera, but I desire to call attention to the fact that my device accomplishes not only this result, but it actually centers the pad 15 so that it does not come in contact with the edges of the opening of the rupture. In order for the wound to heal the edges of the rupture must not be pressed on by the pad and when the walls 3 are placed against the body they will maintain the pad within the wound or opening, but out of engagement with the edges thereof. It is also necessary that as the wound closes some provision must be made for withdrawing the pad, while the outer walls still hold the pad in its central position. This is accomplished in the manner heretofore described.

In Fig. 4 I have shown a modified form of the device in which an outer wall 3^x of

circular contour is provided with an inner pad 15^x which is also circular and concentric with the wall 3^x. The principle upon which the modified form works, however, is precisely that as shown in connection with the preferred form in Fig. 2, the main object being, as above stated, to centralize the pad 15^x within the opening so that it does not come in contact with the edges of the latter.

35

40

I claim:

In a truss, a backing plate provided with laterally extending peripheral flanges, an outer continuous wall disposed within said flanges, said wall being of circular cross section, a bracket carried by said backing and provided with a threaded opening, a screw bolt arranged to extend through said threaded opening and through said backing, a pad disposed within the outer wall and spaced from the latter, said pad being secured to said screw bolt, a supporting member carried by said backing on the opposite side from said pad, a nut on said screw bolt arranged to bear against said backing, and a spring disposed between said nut and said supporting member.
